UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 19, 1927. Serial No. 176,640.

My invention relates to railway traffic controlling apparatus, and particularly to apparatus of the type comprising train-carried governing means automatically controlled from the trackway. One feature of my present invention is the provision of means for capacity coupling between the apparatus on the train and the apparatus in the trackway.

10 I will describe several forms of apparatus embodying my invention, and will then point out the novel features thereof in claims.

In the accompanying drawing, Fig. 1 is a 15 diagrammatic view showing one form of apparatus embodying my invention. Fig. 2 is a diagrammatic view showing a modification of the trackway apparatus shown in Fig. 1 and also embodying my invention. 20 Fig. 3 is a diagrammatic view showing a modified form of coupling between the train-carried apparatus and the trackway apparatus of Fig. 1 and also embodying my invention.

25 Similar reference characters refer to similar parts in each of the views.

Referring first to Fig. 1, the train-carried apparatus comprising a circuit including a generator H of alternating current and a relay C normally energized by the current from the generator H. As here shown, the relay C is of the direct current type, and a full wave rectifier A is interposed between the generator and the relay, although this 30 particular type of relay and means for energizing it from the generator H are not essential to my invention. The relay C controls train governing means of any suitable type, such for example as a brake application valve designated by the reference character EPV. As here shown, this valve is provided with a circuit which includes a front contact 2 of the relay C, and which circuit extends between terminals B and O 35 of a suitable source of current.

The reference character 5 designates a condenser plate which is connected with a

train-carried circuit on one side of the relay C, and the reference character 5^a designates a similar condenser plate which is connected 50 with the train-carried circuit on the other side of the relay C. Located in the trackway are two condenser plates 6 and 6^a, which are arranged to register with, but to be spaced from, the train-carried condenser 55 plates 5 and 5^a. The trackway plates 6 and 6^a are connected by a partial trackway circuit including a reactor 3 and a back contact 4 of a relay R which may be controlled in any suitable manner, such as by traffic 60 conditions in advance. At the frequency of generator H, the inductive reactance of reactor 3 is substantially equal to the capacity reactance of the condensers made up of plates 5—6 and 5^a—6^a.

I will first assume that when the train passes the trackway condenser plates, relay R is energized so that contact 4 is open. The partial trackway circuit is then incomplete and the trackway apparatus has no effect on the train-carried apparatus, so that relay C remains closed. If track relay R is de-energized, however, so that its back contact 4 is closed, the trackway partial circuit acting through the condensers 5—6 and 5^a—6^a 75 shunts enough energy from the relay C to cause this relay to open, because the shunt around relay C is substantially resonant and so its impedance is very low.

Referring now to Fig. 2, the two trackway condenser plates 6 and 6^a are constantly connected by a reactor 3^a, and these two plates are also at times connected through a partial circuit which includes a front contact 4^a of relay R. First assuming that contact 4^a is 80 open, then when a train passes the condenser plates 6 and 6^a, the trackway apparatus causes the train-carried relay C to open, because the inductive reactance of the reactor 3^a is substantially equal to the capacity 85 reactance of the condensers 5—6 and 5^a—6^a. If contact 4^a is closed, however, reactor 3^a is shunted by a path of low reactance, so that the path in shunt to relay C is not resonant 90

at the frequency of generator G, with the result that this relay is not affected. The apparatus shown in Fig. 2 has the advantage that if any part of the partial circuit 5 between plates 6 and 6^a through contact 4^a becomes opened, a stop indication on the train will result, it being understood that the permanent partial trackway circuit through the reactor 3^a is constructed with 10 relatively heavy conductors which are not likely to break or become disconnected.

Referring now to Fig. 3, the apparatus shown in this view is similar to that shown in Fig. 1, except that one side of the train-carried circuit is connected with ground G, as, for example, by connecting it with the frame or an axle of the locomotive, while the other side of the train-carried circuit is connected with the plate 5^a as in Fig. 1. 15 The trackway apparatus comprises a partial circuit one terminal of which is connected with ground at G¹, which will usually be a track rail, and the other terminal of which is connected with a condenser plate 6^a, so 20 located as to register with the condenser plate 5^a on the train. In the form shown in Fig. 3, the reactor, which is here designated 3^b, has an inductive reactance equal to the capacity reactance of the condenser 25 plate 5^a—6^a at the frequency of generator H, so that if contact 4 is closed relay C will be shunted by a path of low impedance with the result that this relay will open. When contact 4 is open, the trackway apparatus 30 has no effect on the train-carried apparatus.

Although I have herein shown and described only a few forms of apparatus embodying my invention, it is understood that various changes and modifications may be 40 made therein within the scope of the appended claims without departing from the spirit and scope of my invention.

Having thus described my invention, what I claim is:

45 1. Railway traffic controlling apparatus comprising a train carried circuit including a source of alternating current and a relay, two condenser plates connected with said circuit on opposite sides of said relay, two 50 condenser plates located in the trackway to register with said two train carried plates respectively, means for at times electrically connecting said trackway plates, and governing means on the train controlled by said relay.

55 2. Railway traffic controlling apparatus comprising a train carried circuit including a source of alternating current and a relay, two condenser plates connected with said 60 circuit on opposite sides of said relay, two condenser plates located in the trackway to register with said two train carried plates respectively, a partial circuit connecting said two trackway plates and including a reactor and a contact, and gov-

erning means on the train controlled by said relay.

3. Railway traffic controlling apparatus comprising a train carried circuit including a source of alternating current and a relay, 70 two condenser plates connected with said circuit on opposite sides of said relay, two condenser plates located in the trackway to register with said two train carried plates respectively, a partial circuit connecting 75 said two trackway plates and including a reactor, a second partial circuit connecting said trackway plates and including a contact, and governing means on said train controlled by said relay.

4. Railway traffic controlling apparatus comprising a train carried circuit including a source of alternating current and a direct current relay, a full wave rectifier interposed between said source and said relay, 80 two condenser plates connected with said circuit on opposite sides of said rectifier, two condenser plates located in the trackway to register with said two train carried plates respectively, means for at times electrically connecting said trackway plates, and governing means on the train controlled by said relay.

5. Railway traffic controlling apparatus comprising a train carried circuit including 95 a source of alternating current and a relay normally energized from said source, a partial circuit located in the trackway and including a contact, means including condenser plates for coupling said train carried 100 and trackway circuits so as to shunt enough energy from said relay to open the relay when the contact in the trackway circuit is closed, and governing means on the train controlled by said relay.

105 6. Railway traffic controlling apparatus comprising a train carried circuit including a source of alternating current and a relay normally energized from said source, a partial circuit located in the trackway, capacity 110 means for coupling said train carried circuit and said trackway partial circuit to shunt enough energy from said relay to open the relay, controlling means included in said partial trackway circuit for rendering said partial circuit ineffective to open said relay, and governing means on the train controlled by said relay.

115 7. Railway traffic controlling apparatus comprising a train carried circuit including 120 a source of alternating current and a relay normally energized from said source, a shunt around said relay including a partial trackway circuit containing a reactor, means including condenser plates for coupling said train carried circuit and said partial trackway circuit, the inductive reactance of said reactor being substantially 125 equal to the capacity reactance of said shunt when said condenser plates are in registry, 130

controlling means associated with said trackway partial circuit, and governing means on the train controlled by said relay.

10 onant at the frequency of said source and including a partial trackway element coupled with the train carried circuit at least in part by condenser plates, and governing means on the train controlled by said relay.

8. Railway traffic controlling apparatus comprising a train carried circuit including a source of alternating current and a relay normally energized from said source, a shunt around said relay substantially res-

In testimony whereof I affix my signature.

LARS O. GRONDAHL.
